UNITED STATES PATENT OFFICE.

EINAR BERGVE, OF NOTODDEN, NORWAY, ASSIGNOR TO NORSK HYDRO-ELEKTRISK
KVAELSTOFAKTIESELSKAB, OF CHRISTIANIA, NORWAY.

PROCESS OF THE MANUFACTURE OF NITRIC ACID.

1,273,991.

Specification of Letters Patent. Patented July 30, 1918.

No Drawing.

Application filed May 18, 1918. Serial No. 235,410.

To all whom it may concern:

Be it known that I, EINAR BERGVE, a subject of the King of Norway, residing at Notodden, in the Kingdom of Norway, have 5 invented certain new and useful Improvements in Processes of the Manufacture of Nitric Acid; and I do hereby declare the following to be a full, clear, and exact description of the invention, such as will enable 10 others skilled in the art to which it appertains to make and use the same.

It is known that concentrated nitric acid may be produced from nitrogen tetroxid, water and oxygen by causing the components 15 to react upon one another under pressure in an autoclave. Such a process is described in the German patent specification 225706. When this process is carried out in the described manner it is however not possible in 20 a reasonable time to obtain a 98% nitric acid, an acid of only about 85% strength being obtained. I have found that it is not possible to obtain an increase in concentration beyond 90% even when the pressure is increased to a very high degree.

According to the present invention a 97% acid may be produced with a satisfactory output from nitrogen tetroxid, oxygen and water, or from nitrogen tetroxid, oxygen and 25 dilute nitric acid and in a short time of reaction by means of also raising the temperature. The most suitable temperature has been found to be about 70° C. It is known, that chemical reactions proceed at a greater 30 speed at higher temperatures than at lower ones, but in the reaction in question it has however hitherto been the practice to cautiously avoid the increasing of the temperature, and a cooling has even been made use 35 of during the reaction, it having been assumed that the highest concentration and the highest output were attainable only at a lower temperature, because the dissociation of the nitric acid and the nitrogen tetroxid 40 is very low at low temperatures.

As stated, the inventor has found how-

ever, that the output as well as the concentration of the acid is increased when the temperature is raised in spite of the fact that the dissociation of the nitric acid and of the 50 nitrogen oxid is hereby increased. The dissociation is suitably compensated for by increasing the pressure and temperature at the same time, so that the working pressure is raised beyond the vapor pressure of the 55 nitrogen tetroxid at the reaction temperature. A pressure of about 20 atmospheres has been found to be suitable. The reaction is hereby attained in a very short time and at the same time it is possible to obtain without difficulties a high percentage nitric acid with a high output calculated upon the nitrogen tetroxid employed. In consequence of the substantial decrease in the time of reaction it is possible to carry out the process 60 65 continuouly and on an industrial scale.

I claim:

1. A process for the manufacture of highly concentrated nitric acid which comprises causing nitrogen tetroxid, oxygen and water 70 to react at a temperature about 70° C. and at a pressure above the vapor pressure of the tetroxid at the temperature used.

2. A process for the manufacture of highly concentrated nitric acid which comprises 75 causing nitrogen tetroxid, oxygen and dilute nitric acid to react upon one another under pressure of about 20 atmospheres and at a temperature of about 70° C.

3. A process for the manufacture of highly 80 concentrated nitric acid which comprises causing nitrogen tetroxid, oxygen and water to react upon one another under a pressure of about 20 atmospheres and at a temperature of about 70° C.

In testimony that I claim the foregoing as my invention, I have signed by name in presence of two subscribing witnesses.

EINAR BERGVE.

Witnesses:

A. VARMAN,
C. FABRICIUS HANSEN.
